US00D912337S

(12) **United States Design Patent** (10) **Patent No.:** **US D912,337 S**
(45) **Date of Patent:** **** Mar. 2, 2021**

(54) **BARK CONTROLLER**

(71) Applicant: **Zhenggen Hu**, Dongta Township (CN)

(72) Inventor: **Zhenggen Hu**, Dongta Township (CN)

(**) Term: **15 Years**

(21) Appl. No.: **29/731,091**

(22) Filed: **Apr. 11, 2020**

(51) **LOC (13) Cl.** **30-99**

(52) **U.S. Cl.**

USPC **D30/199; D10/104.1**

(57) **CLAIM**

The ornamental design for a bark controller, as shown and described.

DESCRIPTION

FIG. 1 is a front, right side, top perspective view of a bark controller showing my new design;

FIG. 2 is a rear, left side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depict portions of the bark controller that form no part of the claimed design.

1 Claim, 8 Drawing Sheets
